UNITED STATES PATENT OFFICE

ALMOS A. DORRANCE AND ARSHAM G. AVAKIAN, OF DETROIT, MICHIGAN, ASSIGNEES
OF ONE-THIRD TO JOSEPH G. WILLIAMS, OF DETROIT, MICHIGAN

TOOTHBRUSH

Application filed April 18, 1929. Serial No. 356,011.

This invention relates to tooth brushes and the object of the invention is to provide a tooth brush having a compartment handle for containing tooth paste and arranged so that the tooth paste may be fed from the handle into the brush.

Another object of the invention is to provide a tooth brush having a double compartment handle in which the handle may be reversed to allow the tooth paste to be utilized from either compartment.

A further object of the invention is to provide a tooth brush having a magazine handle portion for tooth paste and a brush portion including a plunger movable into the magazine portion to force the tooth paste through a duct in the brush portion into the bristles.

These objects and the several novel features of the invention are hereinafter more fully described and claimed and the preferred form of construction by which these objects are attained is shown in the accompanying drawings in which—

Fig. 1 is a section through a tooth brush embodying our invention.

Fig. 2 is an enlarged view showing the brush end of the tooth brush.

Fig. 3 is a section taken on line 3—3 of Fig. 2.

Fig. 4 is a section showing the connections of the tooth paste compartments.

Fig. 5 is a view of the end of the tooth paste duct.

Fig. 6 is a section through an alternative form of tooth brush.

The tooth brush comprises a handle formed of two tubular compartments 1 and 2, shown in Figs. 1 and 4. Each compartment is provided with a closed end 3 having an aperture 4 therethrough and the compartments are connected together by a threaded ring 5 into which the ends of the compartment are threaded. Each compartment 1 and 2 is also provided with an externally threaded open end opposite the closed end 3. The open end of the compartment 1 is threaded into an internally threaded ring 6 and a member 7 is also threaded into the ring 6. A cap 8 is threaded onto the open end of the compartment 2 and is provided with a central thread-

ed aperture which is closed by the filler plug 9. The brush end is made in two parts, a part 10 carrying the bristles and a part 11 which is provided with threads and is adapted to be threaded into the member 7. The members 10 and 11 are connected together by means of a threaded sleeve 12 which also connects the conduits or ducts 13 and 14 of the members 10 and 11. By making the brush end in two parts the part 11 may be inserted through the member 7 and the brush part 10 may be then threaded onto the sleeve 12 to allow the device to be readily assembled. The duct 13 opens through the end of the member 11 into the compartment 1 and the end of the member 11 is provided with a packing 15 in the annular channel 16 provided therefor and this packing fits the inner wall of the member 7. As shown in Fig. 2 the duct 14 leads through a member 17 over which a rubber cap 18 is secured and this cap 18 is provided with a slot 19 in the end through which the tooth paste may be discharged into the bristles 20 of the brush.

In order to fill the handle with tooth paste the compartment 2 is turned in relation to the compartment 1 to bring the apertures 4 into alignment as shown in Fig. 1. The plug 9 is then unthreaded from the cap 8 on the compartment 2 and the end of a tooth paste tube is inserted in its place. By pressing the tooth paste tube tooth paste is forced through the compartment 2 and through the apertures 4 into the compartment 1. When the compartments have been thus filled with tooth paste the cap 9 is replaced and the compartment 2 is turned to bring the aperture 4 of the compartment 2 out of alignment with the aperture 4 of the compartment 1, as shown in Fig. 4, at which time the device is ready for use.

To use the device the handle is held in one hand while the tooth brush portion is rotated with the other hand to unthread the portion 11 from the member 7. It will be noted from Fig. 2 that the companion threads on the members 7 and 11 are similar to pipe threads so that a tight fit may be had at this point. At this time the tooth brush portion may be pushed to the left of Fig. 1 and the end

of the tooth brush and packing 15 acts as a piston to put the tooth paste under compression. The tooth paste is thus forced through the ducts 13 and 14 and through the slot 19 in the cap 18 onto the bristles of the brush. The brush end is then drawn to the right to bring the threads thereon into engagement with the threads in the member 7.

This movement of the brush end tends to 10 produce a vacuum in the chamber 1 thus drawing the tooth paste away from the cap 18 and allowing the slot 19 to close. At this time the brush end is rotated to thread the member 11 into the member 7 at which time the brush 15 may be utilized for brushing the teeth. When all of the tooth paste in the compartment 1 has been utilized the handle is removed by unthreading the compartment 1 from the threaded ring 6 and the handle is turned end 20 for end. At this time the cap 8 is removed and the end 2 is threaded into the ring 6 while the cap 8 with the plug 9 is threaded onto the end of the compartment 1. By this arrangement the tooth paste in the compartment 2 25 may be utilized until the compartment 2 is empty whereupon the handle may be refilled as before by removing the plug 9 and turning the compartments to bring the apertures 4 to alignment. The peripheries of the compartments 1 and 2 adjacent the closed ends 2 are preferably each provided with a mark or 30 indication to indicate when the apertures 4 are in alignment.

A simpler form of the invention is shown 35 in Fig. 6 in which a single compartment 21 is provided into the end of which the handle member 11 is threaded. A cap 8 and a plug 9 are provided on the opposite end of the compartment 21 and the brush end is made sufficiently long so that it may be moved the entire length of the compartment 21 for forcing 40 the tooth paste into the brush bristles.

As will be noted from Fig. 3 by making the brush end 10 of the cross sectional form 45 shown, sufficient space is provided therein for the duct 14 without interfering with the bristles 20 and at the same time the end of the brush is not bulky or ungainly in form. As the slot 19 in the cap 18 is closed except when 50 the tooth paste is forced therefrom the brush may be readily washed out without getting water into the cap 18 or duct 14 and foreign matter cannot readily enter the said cap. This cap is preferably made of soft rubber so 55 as not to injure the teeth when they are being brushed.

From the foregoing description it becomes evident that the device is very simple and 60 efficient in operation, will not easily get out of order, will carry a considerable supply of tooth paste and provides a device which accomplishes the objects described.

Having thus fully described our invention, 65 its utility and mode of operation, what we

claim and desire to secure by Letters Patent of the United States is—

1. A tooth brush comprising a handle formed of two tubular compartments secured together in end to end relation, the adjacent ends of the compartments being closed and being each provided with an aperture, means for keeping the compartments in end to end relation, said means allowing the compartments to be manually rotated to permit 70 or prevent communication between the compartments, a cap threaded onto the outer end of one compartment and provided with a filler plug, an internally threaded member connected to the outer end of the other compartment, a brush member having a plunger thereon movable longitudinally of the last named compartment, the brush member being adapted for threaded relation with the said threaded member, a duct extending 75 longitudinally through the brush member and opening into the brush thereon, and a flexible rubber cap normally closing the end of the duct and provided with a discharge slot. 80

2. A tooth brush comprising a handle 85 formed of two tubular compartments secured together in end to end relation, a cap secured to the end of one compartment and provided with a filler plug, a brush member movable longitudinally of the other compartment and having a plunger thereon fitting the compartment, the brush member having a series of bristles adjacent the end thereof and a duct 90 extending longitudinally therethrough and opening into the bristles, a flexible rubber cap 95 closing the end of the duct and provided with a discharge slot, means for securing the brush member against longitudinal movement, means operable at will for permitting or preventing communication between the compartments. 100

3. A tooth brush comprising a handle formed of two compartments secured together in end to end relation, a filler plug opening 110 into one compartment, a tooth brush portion movable longitudinally of the other compartment and having a plunger thereon fitting the compartment, a member secured to the said compartment and adapted for threaded relation with the tooth brush portion, the tooth brush portion being provided with 115 bristles on the end thereof and with a duct extending longitudinally thereof and opening into the bristles.

4. A tooth brush comprising a handle 120 formed of two compartments secured together in end to end relation, a cap connected to the end of one compartment and provided with a filler plug, a brush portion movable longitudinally of the other compartment and having a plunger thereon fitting the compartment, a series of bristles adjacent the end of the brush portion, a duct extending longitudinally of the brush portion and opening 125 into the bristles, means operable at will for 130

permitting or preventing communication between the compartments.

5. A tooth brush comprising a tubular handle portion, a tooth brush portion having a plunger on the end thereof fitting within the tubular portion and movable longitudinally thereof, a duct leading through the brush portion and opening adjacent the end thereof, a series of bristles mounted in the brush portion about the duct opening, the brush portion being arranged for threaded relationship with one end of the handle portion, the opposite end of the handle portion being provided with a removable plug.
- 10 6. A tooth brush comprising a tubular handle portion, a tooth brush portion having a plunger on the end thereof fitting within the tubular portion and slideable longitudinally thereof, a duct leading through the brush portion and opening adjacent the end thereof, a series of bristles mounted in the brush portion about the duct opening and a flexible rubber cap fitting over the end of the duct and having a discharge slot in the
- 25 end thereof.

In testimony whereof we sign this specification.
